ATTORNEY

UNITED STATES PATENT OFFICE

SIDNEY COHEN, OF NEW YORK, N. Y., ASSIGNOR TO DEFENDER LOCK CO., OF NEW YORK, N. Y., A CORPORATION OF NEW YORK

COMBINATION PADLOCK

Application filed January 26, 1925. Serial No. 4,649.

This invention relates generally to padlocks, the invention having more particular reference to a combination padlock in which the leg or legs of the shackle is engaged by 5 notched rings which are rotatable to different positions to release the shackle by aligning the notches in the various rings, the invention having for an object the provision of a novel and improved combination padlock of this 10 type whose combination may be readily changed at the will of the owner, and which is characterized by convenience of manipulation of the parts in unlocking the padlock.

For further comprehension of the invention, and of the objects and advantages thereof, reference will be had to the following description and accompanying drawing, and to the appended claims in which the various novel features of the invention are more particularly set forth.

Fig. 1 of the drawing is a central longitudinal sectional view of my improved padlock.

Fig. 2 is a face view thereof.

Fig. 3 is a transverse sectional view taken on the line 3—3 of Fig. 1.

Fig. 4 is a like view to Fig. 1 but showing a modification.

Fig. 5 is a like view to Fig. 1 but showing a further modification.

Fig. 6 is a transverse sectional view taken on the line 6—6 of Fig. 5.

Fig. 7 is a face view showing a different modification.

As here shown my improved padlock comprises a casing 10 having a cylindrical cavity in which are received a number of rings 11 that fit snugly therein and rest freely on one another and in the said casing. The casing is 40 closed at one end by an integral bottom member 10' and at its other end by a cap-plate 14 that has a stud 15 projecting therefrom through the rings 11, this stud having a diminished screwthreaded tip 16 that engages in a tapped aperture in the bottom member 10', the stud being of substantially the same diameter as the bore of the rings 11. The cavity in the casing is formed with two diametrically opposed longitudinally extending offsets 18 45 that receive the legs of the shackle, these legs

extending on opposite sides of the series of rings as will be apparent. As here shown the two legs of the shackle are formed separate from one another and each leg comprises inner and outer sections 20 and 21 respectively 55 that are hinged or pivoted to one another as at 22. The inner sections of the shackle legs are formed with notches 23 to receive the rings 11 to retain the shackle in place, while the outer sections of the respective legs curve 60 to meet one another at the line 24, one of the outer sections having a stud 25 on its end that engages in a socket in the adjacent end of the other outer section. When the shackle is locked, the joints between the inner and outer 65 sections are confined within bosses 14' projected from the cap 14 thereby preventing the outer sections of the two legs swinging away from one another, the cap having apertures 70 therein in alignment with the offsets 18 from the cavity in the casing as will be understood. The rings 11 are formed with notches such as 27 that are adapted to be brought into registry with the shackle legs when the shackle is to be released, and with flattened surfaces such as 28 on opposite sides to permit of adjustment of the rings to release one leg of the shackle without interference with the other leg. The rings 11 have studs 30 projecting therefrom into a longitudinal slot 31 formed 75 in one face of the casing 10, so that adjustment of the rings may be effected. The notches 27 in the rings are so arranged that they may be brought into registry with the shackle legs by selective adjustment of the 80 studs 30 to positions with one series engaged with one wall of the slot 31 and another series engaged with the other wall of the slot, while one or more of the rings may be arranged to have their notches register with the 85 shackle legs by selective adjustment of the studs 30 to positions with one series engaged with one wall of the slot 31 and another series engaged with the other wall of the slot 31. 90

In the form of the invention shown in Fig. 4 of the drawing I employ only one movable shackle leg that consists of outer and inner 95 sections 20' and 21' hinged together as at 22, and a fixed leg 33 that projects from the cap 14. This leg 33 has a transverse pin 34 in its outer end that engages in notches such as 35 in the forked end of the leg 21'. Since 100

only one shackle leg projects into the casing 10, there is only about one half the number of retaining rings 11 that are spaced from one another by the washers 36. In this construction the tip 16' on the stud 15' is screwed into a shallow socket in the end of the casing.

In the form of the invention shown in Figs. 5 and 6 of the drawing, the shackle is in the form of a one-piece member having one leg 40 relatively short and extending only into an aperture in the cap 14, the inner part of the other leg 41 being arranged similarly to the leg section 20' shown in Fig. 4, while the alternating notched rings 11 and washers 36 are provided. The leg 41 has a stud 42 projecting therefrom that engages in an arcuate recess 43 in the casing 10. After the shackle leg has been freed by proper adjustment of the rings 11, the shackle can be pulled outward until the stud 42 strikes the cap 14, when the shackle may be rotated on its leg 41 to swing the other leg away from the cap.

In the form of the invention shown in Fig. 7 of the drawing the same general construction as in Fig. 1 is employed except that the two legs 21" of the shackle are each formed of one piece and are united by a chain 45 that may be of any desired length. As here shown these legs project at both ends through the shackle, each projecting pair of ends being arranged for connection to one another by a chain.

Having thus described my invention, what I claim as new and desire to protect by Letters Patent of the United States is as follows:

1. A combination padlock comprising a casing, a center stud adapted to be secured at one end to said casing and provided at its other end with a top closure portion for said casing having spaced shackle openings, a series of rings rotatable in said casing about said stud and formed with notches, a shackle having a pair of legs projecting into said casing through said openings on opposite sides of said rings and having notches in its legs to receive the edge portions of the said rings, the bow portion of the said shackle comprising a chain attached at its ends to the said legs.
2. A combination padlock, comprising a casing, a center stud adapted to be secured at one end to said casing and provided at its other end with a top closure portion for said casing having spaced shackle openings, a series of locking members movably mounted in said casing about said stud, a shackle having two legs one of which is adapted to be engaged in said casing through said openings independently of the other and having notches to receive portions of said movable locking members and a flexible connection between said legs.

In testimony whereof I have affixed my signature.
